UNITED STATES PATENT OFFICE

EDWIN W. NORTH AND LLOYD ANDERSON, OF ROCKFORD, ILLINOIS, ASSIGNEES TO
NATIONAL LOCK CO., OF ROCKFORD, ILLINOIS, A CORPORATION OF DELAWARE

LATCH

Application filed May 7, 1928. Serial No. 275,826.

This invention relates to latches in general and more particularly to latches of the type adapted for use on refrigerators, cabinets, and the like.

5 Latches of the above type are frequently constructed with means for holding the latch bar in inoperative position during the closing of the door, so that it will clear the keeper and not impose unnecessary strains on the latch mechanism during the closing, a trip being provided in conjunction with the keeper to release the latch bar and cause it to engage with the keeper after it has cleared the same. These latches are frequently desired to be 10 used on either side of a door. In order to do this, it is necessary that the latch be adapted for use either as a right or left hand latch.

It is accordingly the primary object of this invention to provide a latch of the above type 15 adapted to cooperate with a trip on the door jamb for causing the latch bar to engage with the keeper after it has cleared the same and which may be readily converted into a right or left hand latch.

20 Other and further objects of this invention will be apparent as the same becomes better understood from an examination of the specification and claims in connection with the accompanying drawings wherein:

25 Fig. 1 represents a fragmentary view partly in section of a door and jamb provided with a latch and keeper embodying this invention.

Fig. 2 is a similar view showing the latch 30 in another position;

Fig. 3 is an elevational view taken from the left of the latch as viewed in Fig. 1,

Fig. 4 is a view similar to Fig. 1 showing

35 the same latch operable as a left hand latch,

Fig. 5 is a section taken at the line 5—5 of

Fig. 4,

Fig. 6 is a view similar to Fig. 4 of a modified form of latch embodying this invention,

Fig. 7 is a section taken at the line 7—7 of

40 Fig. 6,

Fig. 8 is a section taken at the line 8—8 of Fig. 6, showing parts in elevation,

Fig. 9 is an elevational view partly in section of a modified form of latch mechanism 45 embodying this invention,

Fig. 10 is a section taken at the line 10—10 of Fig. 9,

Fig. 11 is a detail plan view of the latch lever of the latter latch removed, and

Fig. 12 is a detail perspective view of one 50 of the parts of the latter latch removed.

Referring to the drawings more particularly, numeral 11 represents a door on which is mounted a latch mechanism represented generally by the reference character 12. A keeper 13 of the usual type is mounted on a jamb 14 adjacent the edge of the door and is adapted to cooperate with the latch mechanism as will be hereinafter described.

The latch mechanism 12 includes a base 15 plate 15 on which is mounted a frame structure 16. A latch lever 17 is supported within the frame 16 above the plate 15 and is pivoted on a pin 18 supported between said plate and frame. A helical spring 19 is mounted above the lever 17 below the top of the frame 16 with its coils surrounding the pin 18 and its ends extending forwardly and compressed together between a pair of integral lugs 20 on opposite sides of the lever 25 forwardly of the pivot. The extreme ends of the spring 19 extend forwardly of the lugs 20 between a corresponding pair of lugs 21 formed integrally upon the frame 16 whereby the lever is yieldingly held in horizontal 30 or central position. Between the plate 15 and the lever 17 there is mounted an abutment member 22 presenting upper and lower shoulders 23 and 24 respectively. This abutment member 22 is mounted concentrically 35 with respect to the lever 17 on the pin 18 and is provided with oppositely extending lateral arms 25. The abutment member 22 may be pivoted about the pivot 18 to bring the shoulder 23 in the position shown where- 40 in it may be engaged by the lever 17 to hold the same in inoperative position, as viewed in Fig. 2 so as to cause said lever to clear the keeper 13 during the closing movements 45 of the door.

During the extreme closing movements of the door, after the lever has cleared the keeper it will engage a trip 26 integral with said keeper which will cause the lever to be 50 disengaged from the shoulder 23 and by the 55

action of the spring 19 engage itself with the keeper.

If it is desired to use the latch as a left hand latch, the abutment member 22 may be pivoted to bring the shoulder 24 instead of the shoulder 23 in position to engage the latch lever and hold the same in inoperative position during the closing movements of the door.

Whether the latch is used as a right hand or left hand latch, one of the arms 25 serves to maintain the abutment member in the desired position. As shown in Fig. 1 in which the latch is used as a right hand latch, one of the arms 25 is adapted to be positioned upon the pivotal adjustment of the abutment member 22 prior to the attachment of the latch mechanism to the door 11 wherein said arm may be engaged by one of the retaining screws 27 for the latch mechanism. In this position, one of the retaining screws holds the particular arm 25 against the latch casing 28 which is also held in position by these screws whereby movement of the abutment member 22 from its adjusted position is prevented. As viewed in Fig. 4, the opposite arm 25 may be similarly engaged by one of the retaining screws 27 for holding the abutment member 22 in the desired position.

In Figs. 6 to 8 inclusive a modified form of latch mechanism is shown including a base plate 29 and a secondary base plate 31 on which is mounted a frame structure 32. The secondary base 31, together with its frame structure 32 is pivoted on the base plate 29 by means of a pin 33. The latch lever 34 is, in this instance, pivoted on the pin 33 within the structure 32 above the secondary base 31 and is yieldingly held in predetermined or central position with respect to said secondary base by means of a helical spring 35, the coils of which surround said pin 33 beneath the top of the structure 32 above said lever 34. The ends of the spring 35 are compressed between a pair of spaced lugs 36 integral with the lever 34. Adjacent to each of the lugs 36 is a lug 37 integrally formed from the structure 32. Each of these lugs 37 cooperates with the opposite lug 36 to further compress the respective ends of the spring when the lever is actuated from its predetermined central position with respect to the secondary base. The secondary base 31 includes an integral abutment member 38 substantially the same as the abutment member 22 and integral arms 39 which are substantially the same as the arms 25. In this case, the abutment member 38 being positioned centrally of the secondary base, the lever is yieldably held in position above said member regardless of the position of said member relative to the base 29.

In this modification, prior to attachment of the latch mechanism to the door by means of

screws 42, said mechanism can be positioned on said door and the lever subsequently turned in a clockwise direction, assuming the latch is to be used as a left hand latch, as viewed in Fig. 6. The abutment member 38 being disposed centrally of the secondary base 31 and the lever being normally held by the spring 35 above the abutment member, the latter will move downwardly as the lever is actuated. This will bring the lower arm 39 in the position shown wherein it may be engaged by one of the retaining screws 42 for securing said abutment member in downward position. This anchors the secondary base and thereafter when the lever 34 is actuated it will move relative to the secondary base against the action of the spring 35. The lever 34 will then cooperate with abutment 38 in the same manner as the lever 17 cooperated with the abutment 22. Prongs 41 are struck from the plate 29 and are adapted to selectively be engaged by the abutment member to further secure the same in the desired position whereby it may not be lifted out away from the base when the lever is actuated.

It will be obvious that the latch of this embodiment may also be used as a right hand latch by actuating the lever in a counter-clockwise direction to bring the abutment member 38 under the other prong 41, prior to attachment of the latch mechanism to the door.

In this embodiment, after the latch mechanism has been secured in position on the door, the latch lever may be actuated the entire distance of its arc of movement between the edges of the housing at the opening therein for the lever from operative to inoperative position or vice versa.

In Figs. 9 and 10 is shown a modified form of latch which differs from the latch just described in the manner in which the latch is yieldably connected to the secondary base. In this modification, a base plate 43 is provided together with a secondary base 44 and pivot pin 45 therefor, the same as in the previous embodiment. The latch lever 46 also, as in the previous embodiment, is pivoted on said pin above the secondary base. A frame structure 47 is mounted on the secondary base 44 and is shaped to form a guide-way for a reciprocal carriage 48. This carriage 48 is slidable longitudinally on the secondary base 44 parallel with the central axis of the secondary base and abutment 49 thereon. The carriage 48 is provided with a pair of depending lugs 51 which are normally held against laterally extending abutments 52 on opposite sides of the latch lever, by the action of a coil spring 53 which tends to move the carriage forwardly on the frame 47 away from the pivot 45. If the lever 46 is pivoted relative to the secondary base 44, the abutment 52 on the side of said lever toward

which it is being pivoted will move rearwardly against its corresponding lug 51 on the carriage to move the same rearwardly on the frame structure 47 against the action of the spring 53. When the lever 46 is released, the spring 53 tending to move the carriage 48 forwardly on the frame structure 47 will tend to restore said lever to central predetermined position with respect to the secondary base 44. As in the previous embodiment movement of the latch lever will not cause relative movement of the lever 46 with respect to the secondary base to take place until the latter has been anchored as shown in Fig. 9, by engagement of one of the retaining screws 54 with one of the arms of the secondary base. After the latch mechanism has been attached to the door and the secondary base 44 has been anchored, to determine whether the latch is to operate as a right hand latch as illustrated, or a left hand latch, the lever may be rocked relative to the secondary base to engage said lever above the abutment member 49. The abutment member 49 will then hold the lever in inoperative position until the same is engaged by the trip on the keeper to cause said lever to engage the keeper.

In the modification just described, it will be apparent that the latch lever may be actuated between a pair of off-center positions either one of which is capable of being the latching position, the opposite then being the inoperative position.

In each modification shown, the abutment member may be adjusted to permit the use of the latch as either a right or left hand latch by swinging said member to one extreme or the other of its arc of possible adjustment. If it is desired to use the latch as an ordinary latch without the trip feature for releasing the latch lever after the same has cleared the keeper the abutment member may be adjusted to a neutral position centrally of such arc of possible adjustment bringing the two arms on the abutment member in position where they may be secured forwardly of the rear retaining screws. In the modification shown in Figs. 1 to 4 inclusive, the abutment member 22 may be adjusted by applying a screw driver or other tool to one of the arms 25 from the rear of the casing and the casing thereafter positioned on and secured to the door. In the other modifications, the casing may be positioned on the door and the abutment member thereafter adjusted by manipulating the handle of the latch lever.

The latch bar 34, Fig. 8 is referred to in the trade as the latch bolt, latch lever, and latch bar, all of these terms enjoying the sanction of good usage, and as applied to a latch of this type meaning the same member. In the claims this member is referred to as the latch bolt.

We are aware that many details may be changed without departing from the principles of this invention and we do not wish, therefore, to be limited to the details shown or described.

We claim:

1. In a latch, the combination of a base, a latch bolt pivoted thereon and capable of being moved to one of two opposite off-center positions, and an abutment member pivoted concentrically with respect to said latch bolt capable of being selectively adjusted with respect to the path of movement of the bolt to a position where it may be engaged thereby for holding the same in either of said off-center positions, the abutment member being provided with a pair of oppositely extending arms, either one of which is adapted to be engaged by one of the retaining screws for the latch for anchoring the abutment member.

2. In a latch, a latch bar and means for pivoting the same, said bolt being movable to either of two opposing offcenter positions, a bolt locking member pivoted concentrically with respect to said bolt and movable to either of two positions where it may lockingly engage said bolt to hold the latter in a corresponding offcenter position, and means for securing said locking member in either of its two said positions.

3. In a latch, the combination of a latch bolt and means for pivoting the same, said bolt being movable to either of two opposite offcenter positions, a bolt locking member movable to either of two positions where it may lockingly engage said bolt in a corresponding offcenter position of the latter, and means for securing said bar locking member in one of its said positions, and means independent of said bolt locking member for yieldably urging said bolt out of either offcenter positions.

4. In a latch, the combination of a latch bolt and means for pivoting the same, said bolt being movable to either of two opposite offcenter positions, a bolt locking member movable to either of two positions where it may lockingly engage said bolt in a corresponding offcenter position of the latter, and means for securing said bolt locking member in one of its said positions, and means independent of said bolt locking member pivoted concentrically with said latch bolt for yieldably urging the latter from inoperative position.

5. In a latch, the combination of a base and a latch bolt pivoted thereon for movement to either of two opposite off-center positions, a bolt locking member and means for selectively fixing the same at either of two positions where it may be engaged by the bolt for holding the bolt in either of said offcenter positions.

6. In a latch, the combination of a base and a latch bolt pivoted thereon for move-

- ment to either of two opposite off-center positions, a bolt locking member and means for selectively fixing the same at either of two positions where it may be engaged by the bolt for holding the bolt in either of said off-center positions, and yieldable means for urging the latch bolt away from either off-center position in which it may be held by said locking member. 80
- 10 7. In a latch, the combination of a base and a latch bolt pivoted thereon for movement to either of two opposite off-center positions, a bolt locking member pivoted concentrically with respect to said latch bolt and means for selectively fixing said member with respect to the path of movement of the said bolt in either of two positions where it may be engaged by the bolt for holding the latter in a corresponding off-center position. 85
- 15 8. The combination with a keeper and trip associated therewith, of a latch mechanism comprising a base and a latch bolt pivoted thereon for movement to either of two opposite off-center positions in either of which positions it may engage with the trip depending upon whether the latch is used as a right hand or a left hand latch, and a bolt locking member and means for selectively fixing the same with respect to the path of movement of said bolt at a position where it may be engaged by the bolt for holding the latter in either of said off-center positions. 90
- 20 9. The combination with a keeper and a trip associated therewith, of a latch mechanism comprising a base, and a latch bolt pivoted thereon for movement to either of two opposite off-center positions in either of which positions it may engage with the trip depending upon whether the latch is used as a right hand or left hand latch, a bolt locking member and means for selectively fixing the same with respect to the path of movement of said bolt at a position where it may be lockingly engaged by the bolt for holding the latter in either of said off-center positions and yieldable means for urging the bolt from whichever off-center positions it may be in when it becomes disengaged from said locking member to thereby cause the bolt to engage the keeper. 100
- 25 10. In a latch, the combination of a base and a latch bolt pivoted thereon for movement between one operative and two inoperative positions, a bolt locking member and means for fixing the same at either of two positions with respect to the path of movement of the bolt whereby the member may lockingly engage the bolt for holding the latter in a corresponding inoperative position. 105
- 30 11. In a latch, the combination of a base and a latch bolt pivoted thereon for movement between one operative and two inoperative positions, a bolt locking member and means for fixing the same at either of two 110
